Patented Jan. 2, 1973

225,721

DRAWER PULL

William Doyle Watt, Jr., Grand Rapids, Mich., assignor to
Keeler Brass Company, Grand Rapids, Mich.

Filed June 28, 1971, Ser. No. 157,816

Term of patent 14 years

Int. Cl. D8—06

U.S. Cl. D8—159

FIG. 1

FIG. 4

FIG. 2

FIG. 3

FIG. 1 is a front elevational view of a drawer pull;
FIG. 2 is a side cross-sectional view thereof taken along
the line III—III of FIG. 1;

FIG. 3 is a side elevational view thereof; and
FIG. 4 is a top plan view thereof.

I claim:

The ornamental design for a drawer pull, substantially
as shown.
